(57) **CLAIM**

The ornamental design for an enclosure for diagnostic analyzer, as shown and described.

DESCRIPTION

FIG. 1 is a front left perspective view of an enclosure for diagnostic analyzer, showing our new design;

FIG. 2 is a front right perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front right perspective view thereof, showing unclaimed environmental structure in dashed lines.

The broken lines shown are included for the purpose of illustrating the environment in which the article resides and form no part of the claimed design.
